United States Patent Office

Des. 219,891

Patented Feb. 9, 1971

219,891

BOAT

William A. Cargile, 101 Jocelyn Hills Road,
Nashville, Tenn. 37205

Filed Sept. 9, 1969, Ser. No. 19,069

Term of patent 14 years

Int. Cl. D12—06

U.S. Cl. D71—1

FIG. 1

FIG. 2

Des 219,891

PAGE 2

FIG. 6

FIG. 5

FIG. 7

FIG. 1 is a perspective view, taken from above the starboard bow, of a boat showing my new design;

FIG. 2 is a perspective view thereof taken from a point above the port quarter;

FIG. 3 is a side elevation view thereof, the other side being identical thereto;

FIG. 4 is a top plan view thereof;

FIG. 5 is a front elevation view thereof;

FIG. 6 is a rear elevation view thereof; and

FIG. 7 is a bottom plan view thereof.

I claim:

The ornamental design for a boat, substantially as shown and described.
